UNITED STATES PATENT OFFICE.

FERRIS A. LIPSCOMB, OF NEW PHILADELPHIA, OHIO.

TOBACCO-PIPE AND HOLDER FOR CIGARS OR CIGARETTES.

1,280,779.

Specification of Letters Patent.

Patented Oct. 8, 1918.

Application filed February 14, 1918. Serial No. 217,138.

To all whom it may concern:

Be it known that I, FERRIS A. LIPSCOMB, a citizen of the United States, residing at New Philadelphia, in the county of Tuscarawas and State of Ohio, have invented a new and useful Tobacco-Pipe and Holder for Cigars or Cigarettes, of which the following is a specification.

This invention relates to tobacco pipes and holders for cigars or cigarettes, and the present application is a continuation in part of the application filed by me on December 12, 1916, Serial No. 136,554, for a patent on tobacco smoking pipes.

15 The object of the invention is to provide a tobacco pipe having means for permitting a current of fresh air, taken from the atmosphere, to be introduced into the smoke passage at a point adjacent to the bowl of the pipe and to be thoroughly mixed with the smoke, to cool the same during its progress back toward the mouth of the smoker, when suction is applied to the pipe bit or mouth piece.

25 Another object is to provide a pipe with means for accomplishing the above purpose which are entirely hidden from view, thus obviating the necessity for altering or otherwise changing the appearance of the pipe 30 to which the improvements are applied.

A still further object is to secure these desired results in a manner to avoid clogging of the smoke passageway, and by means of a minimum number of parts, which may be readily removed from the stem of the pipe, for the purpose of cleansing the same, to remove the accumulations of nicotine, particles of tobacco, etc.

40 A full and complete understanding of the invention may be obtained from a consideration of the following detailed description, taken in connection with the accompanying drawings forming a part of this specification; it being understood that while the drawings show practical forms of the invention, the latter is not confined to strict conformity therewith, but may be changed or modified, so long as such changes or modifications mark no material departure from the salient features of the invention, as specifically pointed out in the claims appended hereto.

In the drawings, in which like reference characters designate corresponding parts in each of the several figures:—

55 Figure 1 is a longitudinal sectional view

of a well known form of tobacco pipe, having the improvements applied thereto, the latter being shown in elevation;

Fig. 2 is a longitudinal sectional view of the pipe bit and member carried thereby;

Fig. 3 is a vertical sectional view on the line 3—3 of Fig. 1, looking in the direction of the arrow;

Fig. 4 is a vertical sectional view on the line 4—4 of Fig. 1, looking in the direction of the arrow;

Fig. 5 is a detail section on the line 5—5 of Fig. 1;

Fig. 6 is a view of a somewhat modified form of pipe, showing the parts of the improvement in separated position;

Fig. 7 is a view illustrating another modified form of the invention, the bit and parts carried thereby being removed from the stem of the pipe;

Fig. 8 is a longitudinal sectional view of the same, showing the parts assembled and ready for use;

Fig. 9 is a view partly in section of a cigar or cigarette holder having the improvements applied thereto.

Referring to the drawings, and more particularly to Figs. 1 to 5 inclusive, there is shown a pipe bowl 1 having an integral projecting stem 2, which may be of any well known form. The stem 2 is provided with a relatively large inwardly tapered bore 3 extending from its outer end inwardly to a point adjacent to the bowl 1, with which it communicates by a somewhat reduced passageway 4, and the outer end of the stem 2 is provided with the usual ferrule 5 for the purpose of strengthening the same.

In the form of the invention under consideration, the bit or mouth piece 6, which may be made of any desirable material and shaped in accordance with the well known forms, is provided with an integral core or extension 7, which is tapered to correspond with the tapered bore 3, although of considerably less diameter than the latter. The inner, smaller end of the tapered core or extension 7 is adapted to lie adjacent to the reduced passageway 4, when the bit 6 is fully introduced into the stem 2 of the pipe, as clearly shown in Fig. 1 of the drawings.

At the point of juncture between the core 7 and the bit 6, the latter is reduced in diameter, as indicated at 8, to provide a shoulder 9 which abuts against the outer, inturned end of the ferrule 5, thus forming a tight

joint at this point, to prevent the leakage of smoke when the pipe is in use.

The bit 6 is provided with a short longitudinal groove 10 extending across the reduced portion 8 and also into the inner end of the bit 6, at a point beyond the inturned end of the ferrule 5, for a purpose to be described.

The bit 6 is provided with the usual smoke

10 passage 11, which, however, does not traverse throughout the entire length of the core or extension 7, but communicates at a point near the reduced portion 8 with a radially extending smoke inlet 12.

15 A spirally arranged tube or conduit 13 is adapted to surround the tapered core or extension 7 and to snugly fit the same in order to prevent leakage between the several spaces formed by the coils of said spiral tube. The outer tapered surface of the spiral tube or conduit 13 snugly fits the tapered bore 3 of the pipe stem 2, and likewise prevents the leakage of smoke at its outer periphery.

20 The outer, larger end of the spirally arranged tube 13 is provided with a short longitudinally disposed extension 14 having an outturned, radially disposed terminal 15, the extension 14 and terminal 15 being 25 adapted to be seated in the aforesaid groove 10, and to lie flush with the reduced portion 8 and the outer surface of the bit 6 respectively, so that the said terminal 15 will be located contiguous to but beyond the outer 30 end of the ferrule 5, for the purpose of admitting air into the spirally arranged tube 13.

35 The inner open end 16 of the said tube is located adjacent to the inner end of the tapered core or extension 7, and is preferably 40 elevated above the bottom of the tapered bore 3, as shown in Fig. 1, so that nicotine or particles of tobacco may not enter into the tube. The smoke inlet 12 is located between the coils of the tube 13 and near the 45 outer end thereof, so that it will be seen that when the pipe is in use, a suction will be created in the passageway 11, toward the mouth of the smoker, thus causing an outward draft between the coils of the tube 13,

50 as indicated by the arrows in Fig. 1 to draw upon the burning tobacco within the bowl 1, and causing the smoke to follow the course indicated by said arrows. At the same time, a similar action is brought to bear through 55 the open end 16 of the tube 13 causing an inflow of fresh air from the atmosphere, through the entrance 15, and in an opposite direction through the coils of the tube to said outlet 16, where the air is caused to mix 60 with the smoke and to cool the same. The combined smoke and air is further cooled by being caused to travel back between the coils of the air tube 13, which are constantly being affected by the inflowing air there- 65

The form of the device disclosed in Figs. 7, 8 and 9 is deemed the preferred form thereof, and differs structurally from the device as hereinbefore described, although the function is precisely the same. 70

In this form, the bit 6 may be detachable from the core or extension 7, as illustrated, and held together by a threaded connection 17 in a well known manner. The bit 6 is provided with an axial bore or passageway 75 18 which communicates through the connection 17 with the smoke inlet 19 formed in the core or extension 7, similar to the first described form of the invention.

The core or extension 7 is provided with 80 a pair of integral spirally arranged flanges 20 spaced apart sufficiently to provide a continuous spiral air conduit 21, the outer peripheral edges of said flanges being tapered to conform to the bore 3, thus preventing 85 any leakage of smoke along its outer periphery. Between the convolutions of the spiral flanges 20 a continuous smoke passageway 22 is formed in a manner similar to the previously described form, and it will be readily 90 seen that the action of the device is precisely the same.

The air passageway 21 communicates at its outer end with the air intake port 23, which is formed by providing a relatively 95 shallow groove in the enlarged end of the core or extension 7, to extend slightly beyond the ferrule 24, in order to communicate with the atmosphere.

The improved device is capable of being 100 readily applied to a cigar or cigarette holder, as illustrated in Fig. 9 of the drawings, wherein the construction and operation is precisely the same as last described. It will be noted that the holder is formed of a bit 105 or mouth piece 6, a stem 2 having a tapered bore 3, and a bowl 1.

It will also be noted that in the form shown in Figs. 1 to 5 inclusive, the diameter of the air pipe 13 is less than the space between the coils of the pipe, with the result that the air passage has a less area than the smoke passage. The same plan is carried out in the construction shown in Figs. 7 to 9, inclusive, in which the spirally arranged 115 flanges 20 are disposed in pairs, and the space between each individual member of the pair of flanges is less than the space between the pairs themselves, with the result that the air passage is of less area than the smoke 120 passage. By this arrangement, the draft through the mouth piece is not impeded, and yet the smoke does not travel so fast that it is not sufficiently cool by the time it reaches the mouth of the smoker. 125

From the foregoing, it will be seen that means have been provided for cooling the smoke as it issues from a tobacco pipe into the mouth of the smoker, which may readily be applied to almost any well known form 130

of pipe or cigar or cigarette holder, and which is capable of being produced by the use of a single additional member which is entirely concealed within the stem of the 5 pipe.

With the use of the present smoke cooling device, tobacco smoking is rendered less injurious to the smoker, inasmuch as there is a fresh current of air laden with oxygen, 10 mixed directly with the smoke, which contains very little oxygen and a large quantity of carbon dioxide; therefore, diluting the carbon dioxide gas and eliminating, to a large extent, the injurious effects of hot smoke 15 upon the tongue and mouth of the smoker. In addition, it prevents the absorption of much nicotine for the reason that heat is a great stimulator of absorption, and the abnormal flow of saliva usual with the use of 20 ordinary pipes is partially prevented, thus allowing the system to be benefited by these necessary juices, etc., and in addition, it has a more soothing and quieting effect on the smoker than has the hot smoke drawn from 25 an ordinary tobacco pipe.

What is claimed is:

1. A tobacco pipe or holder having a stem formed with a bore, a removable bit provided with a longitudinal bore for a portion 30 of its length, said bit having alternately arranged spiral air and smoke passages, said passages having a common communication at their inner ends with the bowl of the pipe or holder and communicating respectively at 35 their outer ends with the atmosphere and with the longitudinal bore of the stem.

2. A tobacco pipe or holder having a stem and a bit provided with a longitudinal bore for a portion of its length, said stem being 40 provided with interiorly arranged alternating air-inlet and smoke-outlet passages connecting with each other and with the bowl of the pipe or holder at one end, the air inlet passage communicating at its other end with 45 the atmosphere, and the smoke outlet passage connecting at its other end with the longitudinal bore of the bit.

3. A tobacco pipe or holder having a stem provided with an inwardly tapered bore 50 communicating with the bowl of the pipe or holder, a removable bit having a tapered inner end of a diameter smaller than said tapered bore and adapted to enter the same, said bit having a longitudinal bore for a portion 55 of its length, and spirally arranged spaced walls carried by the tapered end of the bit and contacting with the walls of said tapered bore and defining alternately arranged spiral air and smoke passages, communicating with each other and with the bowl of the pipe at their inner ends and with the atmosphere and the longitudinal bore of the bit at their respective other ends.

4. A tobacco pipe or holder comprising a 60 bowl having a stem provided with a tapered

bore communicating with the bowl, a removable bit having a reduced, tapered inner end and a bore extending for a portion of its length, spirally arranged flanges located between the tapered inner end of the bit and 70 the walls of the tapered bore and defining alternate air and smoke passages open at their inner ends so as to communicate with the bowl of the pipe or holder, said air passage having its other end open to the atmosphere and said smoke passage connecting at its other end with the said bore of the bit.

5. In a smoking pipe or holder for cigars and cigarettes characterized by the employment of a bore leading from a bowl, the combination with said pipe or holder, of a bit, 75 means for forming two independent spiral passages in the interior of said bore substantially throughout the length thereof, one of said passages being an air passage and the 80 other a smoke passage, said passages communicating with the bowl at the inner end, a longitudinal bore in the bit communicating with the outer end of the smoke passage, and an air intake port connecting with the 85 outer end of the air passage.

6. In a smoking pipe or holder for cigars and cigarettes characterized by the employment of a bore leading from a bowl, the combination with said pipe or holder, of a bit, 90 means for forming two independent spiral passages in the interior of said bore substantially throughout the length thereof, one of said passages being an air passage and the other a smoke passage, the air passage being 95 of less cross sectional area than the smoke passage, said passages communicating with the bowl at the inner end, a longitudinal bore in the bit communicating with the outer end of the smoke passage, and an air intake 100 port connecting with the outer end of the air passage.

7. A bit for smoking pipes and holders for cigars and cigarettes, having its inner portion provided with two spiral passages, 110 which are continuous and are non-communicating with respect to each other, one passage being a smoke passage and the other an air passage, an axial longitudinal bore located in the outer portion of the bit and open 115 at both ends, the inner end of said bore leading out to the surface of the bit at an intermediate point of its length, and joining and having communication with the outer end of the smoke passage, and a short longitudinal 120 groove on the outer face of the bit and communicating with the outer end of the air passage.

8. In a pipe or holder for cigars and cigarettes having a stem provided with a bore, the combination with said stem, of a bit provided with a longitudinal bore leading from its outer end inwardly for a portion of the length of the bit and continued out to the surface of the bit, a solid core provided on 125

- the inner end of the bit, a pair of spiral passages arranged side by side and extending from the inner end of the core outwardly, one passage being a smoke passage and the other an air passage, the length of the passages being such that when the bit is inserted within the bore of the stem, the outer ends of said passages will terminate short of the outer end of said bore, the inner end of the longitudinal bore of the bit opening into the outer end of the smoke passage, and an intake port for the air passage leading from the outer end thereof to a point outside the bore of the stem.
- 15 9. In a pipe or holder for cigars or cigarettes, the combination with the pipe or holder having a stem provided with a tapered bore, of a bit having a tapered inner portion provided with a pair of spiral flanges or walls arranged longitudinally

along said inner portion of the bit, said flanges tapering to correspond with the bore and closely fitting the latter and forming continuous spiral passages arranged side by side, the outer portion of the bit having a 25 longitudinal bore open at its outer end and extending inwardly and communicating by a lateral branch with the inner end of one of the said passages, and an intake port communicating with the outer end of the other 30 passage and leading to a point beyond the stem.

In testimony that I claim the foregoing as my own I have hereto affixed my signature in the presence of two witnesses.

FERRIS A. LIPSCOMB.
